ENGINE STARTING MECHANISM

Raymond P. Lansing, Montclair, N. J., assignor to
 Eclipse Aviation Corporation, East Orange,
 N. J., a corporation of New Jersey

Application May 12, 1930, Serial No. 451,830
 Renewed March 2, 1938

5 Claims. (Cl. 123—179)

This invention relates to engine starting apparatus, and more particularly to devices of the inertia type for use in starting internal combustion engines.

5 One of the objects of this invention is to provide novel unitary starting mechanism.

Another object of the invention is to provide an engine starter of the inertia type embodying novel means which will transmit a predetermined torque only, whereby the parts are protected against excessive strains.

10 Another object is to provide an engine starter of the inertia type in which the inertia member may slip relative to the remaining parts when the resistance of the remaining parts becomes excessive.

15 Another object of this invention is to provide an engine starter of the inertia type which will transmit a predetermined torque only and which will prevent excessive shocks from being transmitted to the engine on starting.

20 Another object of this invention is to provide a novel combination of elements giving a simple and compact construction which is efficient for the purpose intended and reliable in operation. These and other objects will be more apparent from the following description of the drawings.

25 Three embodiments of the present invention are illustrated in the accompanying drawings, but it is to be expressly understood that the drawings are for the purpose of illustration only and are not designed as a definition of the limits of the invention, reference being had for this purpose to the appended claims.

30 Fig. 1 is a longitudinal section of an engine starter embodying the present invention;

35 Fig. 2 is a detailed view of the lower section of a shaft on which the inertia member and clutch elements are mounted, as shown in Fig. 1, the upper end of the shaft being cut away for clarification, although shown fully in Fig. 1;

40 Fig. 3 is a detailed fragmental plan view of one of the gears shown in Fig. 1;

45 Fig. 4 is a perspective view of the resilient driving connection between the driven clutch jaw and flywheel of the engine shown in Figs. 1, 5 and 6;

50 Fig. 5 is a longitudinal section of another embodiment of the present invention.

55 Fig. 6 is a longitudinal section of still another embodiment of the invention; and

Fig. 7 is a side elevation view of the externally threaded nut which constitutes part of the assembly shown in Fig. 1 and in Fig. 6.

Starter mechanisms incorporating the present invention comprise an inertia member in which

substantially all of the energy for cranking the engine is adapted to be stored. Reduction mechanism is operatively connected with the inertia member and with a manually operated actuating means so that the inertia member may be energized by means of a hand crank through the reduction gearing. A driving mechanism is also connected with the reduction gearing for transmitting the energy stored in the inertia member to the engine to be started through the reduction gearing.

Referring now to the drawings wherein like reference characters indicate like parts throughout the several views. As illustrated in Fig. 1 the starter is enclosed in a casing having an inner part 8, an intermediate part 9, and an outer part 10 held in assembled relation by means of bolts 11 extending through aligned apertures in the several parts. Any suitable means may be provided for attaching the casing to the engine to be started such as brackets (not shown). An apertured diaphragm 12 is attached to the outer casing part 10 in any suitable manner such as by cap screws (not shown) and which in turn carries a cover 13 forming a chamber. This diaphragm 15 has a circular boss 14 forming a seat for anti-friction bearing 15 inserted in the aperture and which is held in place by a circular plate 16 attached to diaphragm 12 by means of bolts 17. Laterally spaced from the bearing 15 and within the cover 13 forming a seat therefor is an anti-friction bearing 18.

A hollow shaft 19 is rotatably mounted in the bearings 15 and 18 having an annular shoulder 20 for engaging the inner part of bearing 15. Loosely mounted on shaft 19 is an inertia member having a hub 21, a web 22, and a flange 23, adapted to be rotated in the chamber formed by the diaphragm 12 and cover 13. The inertia member is supported on the shaft 19 by a friction plate 24

40 rotationally rigid with the shaft and resting on the other side of the bearing 15 from that engaged by the shoulder 20 of the shaft 19. A second friction disc 25 rotationally rigid with the shaft 19 but free to move longitudinally thereof 45 engages the other side of the hub 21 of the inertia member. These friction plates 24 and 25 constitute a yielding driving connection from the shaft to the flywheel for transmitting a predetermined torque, dependent upon the pressure applied.

The pressure is applied by a spring 26 located between the disc 25 and an abutment 27, which is adjustable longitudinally by means of a nut 28 for varying the pressure and which may be locked in any set position by a nut 29. As shown in detail 50 55

in Fig. 2, the shaft 19 has a cylindrical end portion 30 with flat sides to cooperate with similar flat sides in the bearing 18. Adjacent this end is provided a screw threaded portion 31 for receiving the nuts 28 and 29. Below the threaded portion 31 is an enlarged boss 32 with flat sides 33. The flat sides of this boss cooperate with the apertures in the friction discs 24 and 25 for making the same rotationally rigid therewith. The aperture in the hub 21 of the inertia member is circular allowing it to rotate freely on the shaft. On the lower end of shaft 19 and formed integrally therewith is a pinion 34.

The reduction gearing connected with the inertia member comprises a gear 35 in constant mesh with the pinion 34 formed integral with the shaft 19. Gear 35 is fixed to a stub shaft 36 by means of a nut 37 on the threaded extension 38 of the shaft. This stub shaft 36 is rotatably mounted in anti-friction bearings 39 and 40 positioned in an apertured web 41 integral with the casing part 10. The web is formed with a boss 42 and a peripheral recess 43 forming a seat for the bearing 39 and an expansion bushing 44 respectively, the bearings having a press fit with the bushing. On the lower end of stub shaft 36 and formed integral therewith is a spur pinion 45 in constant mesh with a spur gear 46. As more clearly shown in Fig. 3, a disc like member 47 is rigidly attached to the spur gear 46 by means of splines 48 and 49 projecting from the two respective members. Set screws 50 are screw threaded into tapped holes formed between the splines of the two members to prevent longitudinal movement relative to each other. A beveled pinion 51 is rigidly attached to the member 47 by means of a nut 52 on a threaded extension 53 of the member 47.

The manually operated actuating means for the reduction gearing comprises a shaft 54 having a pin 55 extending transversely through the shaft externally of the casing and adapted to be engaged by a removable crank (not shown). This shaft 54 has formed integrally therewith on the opposite end, an internal gear 56. The internal gear 56 is in constant mesh with a pinion gear 57 formed integral with a shaft 58 and transmits motion to the bevel pinion 51, through the bevel gear 59 rigidly attached to the other end of the shaft 58 by means of a nut 60 on the threaded extension 61 of the shaft. The shaft 58 is rotatably mounted in a housing 62 inserted in an aperture in the casing part 10, and held in position by means of set cap screws 63. Shoulder 64 is provided on the housing to cooperate with a corresponding shoulder on the housing part 10 to properly position the same. Bushings 65 are positioned at either end and within the housing 62 for rotatably supporting the shaft 58 and correcting any slight inaccuracies of the bore. The shaft 54 is rotatably supported in a housing part 64 attached to the housing 62 by means of bolts 67 and has bushings 68 and 69 for rotatably supporting the shaft. A thrust washer 70 is provided between the internal gear 56 and the housing 64. A washer 71 is provided at the other end between the end of the housing 64 and a snap ring 72 positioned in a groove on the shaft 54 for holding the same in its proper longitudinal position.

The driving mechanism connected with the reduction gearing comprises a hollow cylindrical extension 73 of the ring gear 46 having an internal long lead thread 74, the end of which 75 thread on the upper side constitutes a shoulder

15. This ring gear 46 and cylindrical extension 73 are rotatably mounted in a casing extension 76 of the intermediate casing part 9, by means of the anti-friction bearing 77. A bushing 78 is provided for correcting any slight inaccuracies in the bore of the casing extension 76 and forming a bearing surface. Within the cylindrical extension 73 is positioned a nut 79 which as more clearly shown in Fig. 7 has external long lead threads 80, a shoulder 81, and internal grooves 10 82. A driving member 83 is positioned within the extension 73, having splines 84 that engage with the grooves 82 in the nut forming a rigid driving connection therebetween but allowing a longitudinal movement. This driving member 15 83 extends outwardly of the casing extension 76 and has a flange against which nut 79 abuts when the latter advances by reason of the screw action which occurs between threads 74 and 80 in response to initial rotation of extension 73. This 20 flange on driving member 83 is provided with a notched outer surface constituting clutch jaws 85 for engagement with clutch jaws 86 of a member of the engine to be started.

The driving member is held in a retracted position out of engagement with the member of the engine to be started by means of a rod 87 which extends through the driving member 83 and the hollow shaft 19 at their axes of rotation to the outside of the cover 13. Attached to this rod 87 30 is a push-button 88 by means of a pin 89. On the other end of the rod 87 from the push-button is a nut 90 engaging the under part of the driving member and held on the rod by means of a cotter pin 91. A spring 92 positioned between the 35 push-button and cover 13 normally holds the rod 87 and driving member in their retracted positions. A shoulder 93 is provided on the rod 87 for engagement with a washer 94 which acts as an abutment for spring 95 which engages at its 40 other end with the driving member to hold the same against the nut 90.

The driving connection between the starter mechanism and the flywheel of the engine to be started will now be described. A detailed view 45 of this driving connection which is common to all three modifications is shown more clearly in the perspective view of Fig. 4. The flywheel 96 of the engine to be started is held in its proper position on the threaded end of the crank shaft 50 97 by means of a nut 98. The clutch member having teeth 86 is secured to a plate 99 having a peripheral flange 100 by any suitable means such as rivets 101. Mounted on the opposite side of the plate from the clutch member are angularly 55 disposed studs 102 held in position by a head peaned over on the front side of the plate. Also angularly disposed on the plate 99 but on different diameters from the studs 102 are slots 103 concentric with the axis of rotation. Positioned on the under side of the plate 99 and within the flange 100, is a disc of resilient material 104, such as rubber, having apertures for receiving studs 101 and apertures in alignment with the slots 103 at one end. Bushings 105 are inserted in these apertures for receiving cap screws 106 which extend through the plate 99 and resilient disc 104, and are adapted to be screwed into tapped holes in the flywheel 96. With this arrangement the rotation of the jaw clutch having teeth 86 is transmitted to the flywheel 96 through the resilient disc 104 by means of the studs 102 and cap screws 106 preventing any shocks from being transmitted to the engine. 71

The operation of the starter mechanism is as 7

follows: The operator attaches a hand crank to the pin 55 and rotates the shaft 54, which motion is transmitted at an increased rate by the internal gear 56 and pinion gear 57 to the shaft 58 and gear 59. Gear 59, being in constant mesh with the bevel pinion 51, will rotate the member 47 rigidly secured to the spur gear 46. The ring gear 46, being in constant mesh with the pinion 45, will rotate the stub shaft 36 and the gear 35 attached thereto and which in turn will rotate the pinion 34 and hollow shaft 19 at a greatly increased rate. The friction discs 24 and 25 being rotationally rigid with the hollow shaft 19 and engaging the hub of the inertia member 21 with a predetermined friction, as determined by the compression of the spring 26, will transmit their rotation to the inertia member to energize the same. When the inertia member has stored sufficient energy to start the engine, push-button 89 is depressed and the rod 87 forced downwardly together with the washer 94. The spring 95 will then force the driving member 83 into engagement with the member of the engine to be started by means of the teeth 85 and 86, with a yielding pressure. The rotation of the inertia member is then transmitted back through the gears 34, 35, 45, and 46, and cylindrical extension 73. The rotation of the extension 73 will advance the nut 79 into abutment with the flange 30 of member 83, in which position it serves to firmly hold the driving member 83 through the clutch jaws 85 in engagement with the clutch jaws of the engine member 86. Further rotation of the extension 73 will then be transmitted 35 through the nut 79 to the driving member 83 by means of the spline 84 and rotate plate 99 of the member of the engine to be started. When the torque is first supplied to resilient disc 104 it will allow a relative movement between the studs 102 and the cap screws 106, preventing the sudden shock from being transmitted directly to the crank shaft. If the torque becomes excessive, the inertia member will slip relative to the friction discs 24 and 25 preventing any strains or possible 40 breakage of parts. The predetermined torque which will be transmitted from the inertia member to the remaining parts may be determined by the proper adjustment of the spring 26 by nut 28. After the engine starts and is running under 45 its own power, it will rotate at a greater speed than the driving member and rotate the nut 79 relative to the extension 73. This rotation of the nut will retract the same and allow the spring 92 to retract the rod 87 and driving member 83 out 50 of engagement with the engine member to its normally disengaged position.

If, at any period of the cranking process, there is a momentary tendency on the part of the crank-shaft to overrun, jaw clutch 85, after moving back slightly against the spring 95 and nut 79, will be returned (by the combined pressure of said spring and nut) into full mesh with jaw clutch 86, and the cranking action continued until the engine is capable of continuing in motion 55 on its own power. It is to be understood that the operator maintains button 88 depressed until completion of the cranking action.

In the embodiment disclosed in Fig. 5, a different arrangement of elements is provided. In this embodiment the hollow shaft 19 is rotatably mounted in bearing 15 in the apertured diaphragm 12 and the bearing 18 mounted in an extension 41' of web 41. The hollow shaft 19 is provided with a shoulder 110 for engaging the inner part of the bearing 15 and a tapered end 111

to fit a corresponding tapered inner part of the bearing 18 for providing a rigid connection of the shaft with the inner rotating part of the bearing and for maintaining the bearing seated in the apertures of the diaphragm and web. The hub 21 of the inertia member rests directly on the inner part of the bearing 15 and is held in rigid contact with the same by means of a nut 112 threaded on the threaded end of shaft 19.

An internal ring gear 113 meshes with the pinion gear 45 formed integral with the stub shaft 36. This internal gear 113 is rigidly mounted in a member 114 having a part 115 to which is attached an extension 116 by any suitable means such as a sweated joint. The part 115 at its lower 15 end is cut away to form splines 117. A bushing 118 is provided to form a bearing surface for the extension 116. A hollow cylindrical member 119 with internal long lead threads corresponding to those of nut 79 is positioned within the extension 116. A series of friction discs 122 are provided for connecting the extension 116 to the hollow cylindrical member 119 and adapted to transmit a predetermined torque only. These friction discs are of two sets in alternate relation 20 and the discs of one set are connected with the spline 117 of extension 116, while the discs of the other set, disposed alternately with the discs of the first set, are similarly connected to the cylindrical member 119. The frictional engagement 25 between the sets of discs may be adjusted to any desired amount by means of spring 123. The friction discs 122 are held in position by means of rings 124 and 125 and a series of springs 123. These springs are centered by means of depending lugs 126 from the ring 125. The other end of the springs 123 are seated on an adjustable ring 127 having a screw threaded engagement with the member 119 and are provided with a series of apertures 128 for engagement by a spanner 40 wrench. By advancing or retracting the ring 127 the compression of the springs 123 may be adjusted for varying the frictional engagement of the alternate discs 122. The hollow cylindrical member and disc clutch assembly is retained in position by means of a snap ring 141. A detachable dust cover 129 is provided having a slotted resilient skirt with a protruding rib adapted to engage a cooperating recess in the casing extension 76. A snap ring 130 insures positive engagement 50 of the cover with the extension.

The manually operated actuating means for the reduction gearing comprises the bevel gear 59 held in its proper longitudinal position on the shaft 131 by means of a nut 132 on the threaded extension of the shaft. A sleeve 133 abuts against the other side of the hub of gear 59. This sleeve surrounds the shaft 131 and is held in position by means of collar 134 fastened to the shaft by means of a set screw 135. A pin 136 extends transversely of the shaft 131 for engagement by a removable crank (not shown). Bushings 137 and 138 are positioned at each end internally of the sleeve for supporting the shaft 131 and correcting any slight inaccuracies in the respective diameter. A sleeve 140 is provided in an aperture of the casing part 9 for rotatably supporting the sleeve 133 and is held in its position in the casing by means of a set screw 142. The assembly 70 of shaft, gear, and sleeve is adapted for longitudinal movement in the journal 140 to demesh the gears 59 and 51. To limit the longitudinal movement when the gears are in mesh a shoulder 143 is provided on the sleeve which abuts against a 75

shoulder 144 formed on the outside end of the journal 140.

The operation of the mechanism in this embodiment of the invention is similar to the modification disclosed in Fig. 1. The operator attaches a hand crank to the shaft 131 by means of the pin 136 and slides the shaft and sleeve 133 until the shoulder 143 abuts with the shoulder 144 at which time the gear 59 and pinion 51 will be in mesh. The shaft is then rotated by the crank which motion is transmitted through the gears 113, 45, 35, and 34 integral with the hollow shaft 19 and the inertia member rigidly attached thereto. After sufficient energy has been stored in the inertia member to start the engine, the cranking shaft 131 is moved longitudinally out of engagement with the actuating mechanism. The push-button 88 is depressed and the driving member 83 moves into engagement with the driven member of the engine to be started. The motion of the inertia member is then transmitted back through the shaft 19, gears 34, 35, 45, 113 to the cylindrical extension 116. The friction discs 122 will then transmit a predetermined torque to the member 119. Rotation of the member 119 advances the nut 79 and firmly holds the driving member 83 in engagement with the driven member. If the resistance of the engine is greater than the torque which can be transmitted through the friction disc 122, a relative slippage will occur preventing excessive strains or breakage of parts. When the engine starts to run under its own power the nut 79 will be retracted and the spring 92 will disengage the driving member from the driven member of the engine.

In the embodiment of the invention disclosed in Fig. 6 the hollow shaft 19 is rotatably mounted in the bearings 15 and 18 and has a threaded connection 149 at one end with the inner part of the bearing 18 and the annular shoulder 110 engaging the under part of the bearing 15 holding the respective bearings against their seats. The adjustable abutment 27 against which the spring 26 rests is held between the nuts 28 and 29. Friction discs 24 and 25, as in Fig. 1, are rotationally rigid with the hollow shaft 19 and engage the hub 21 of the inertia member.

The internal ring gear 113 is rigidly mounted in a member 150 which has an extension 151 attached thereto by means of rivets 152. This cylindrical extension 151 is rotatably mounted in a bushing 153 carried by the casing extension 16. This bushing 153 may be in the form of a graphite packing for lubricating the bearing surface. This cylindrical extension 151 has internal long lead threads 14 that cooperate with the long lead threads 80 on the exterior of the nut 79 which in turn is splined internally to the driving member 83 as in Fig. 1.

An apertured diaphragm 154 is provided in an extension of the cover 13 against which the compression spring 92 abuts. The other end of the spring seats against the under part of the push-button 88 which in this modification extends into the cover 13 which acts as a guide for the same.

In Figs. 5 and 6, the reduction gear transmission is the same as is also the longitudinally movable actuating means for the reduction gearing. The operation of the elements in this modification can be readily understood in view of the description of the operation of the modification shown in Fig. 1, and need not be explained.

Thus it will be seen that a compact, efficient starting mechanism has been provided which prevents undue strains from being subjected to

the parts, allowing the parts to be made in a light compact form, and also providing a starter in which any sudden shocks in starting are prevented from being directly applied to the crank shaft of the engine.

It will be obvious that the invention is not limited to the specific forms described and illustrated in the drawings, but is capable of a variety of mechanical embodiments. Various other changes which will now appear to those skilled in the art may be made in the form, details of construction, and arrangement of parts without departing from the spirit of the invention, and reference is therefore to be had to the appended claims for a definition of the limits of the invention. That portion of the disclosure not claimed herein is the subject of claims in my divisional application, Serial Number 113,738, filed December 1, 1936.

What is claimed is:

1. In an engine starter, a longitudinally movable driving member having an axial bore, a hollow shaft coaxial with the driving member, reduction means connecting the driving member and shaft, an inertia member mounted on the shaft and in driving engagement therewith, a rod extending through the bore of the driving member and the hollow shaft for controlling the longitudinal movement of the driving member, a driven member mounted on the engine crank-shaft in a position to be engaged by said driving member, and an axially movable sleeve surrounding said rod and physically abutting said driving member to tend to prevent disengagement of said members prior to completion of the cranking process.

2. In an engine starter, a housing, a hollow shaft rotatably mounted in said housing, a driving member on said shaft, a longitudinally movable engine engaging member mounted in said housing in driven relation with the shaft, a friction clutch and reduction gearing connecting said shaft and engine engaging member, a rod connected to the engine engaging member at one end and to a manually operable member at the other end, said rod extending through the hollow shaft, a spring coiled about said rod for holding the rod and engine engaging member in a normally retracted position, and a threaded sleeve surrounding said rod and physically abutting said driving member to tend to prevent disengagement of said engine engaging member.

3. The combination with an engine member of means for driving said member comprising a one-way driving connection including coaxially disposed driving and driven clutch jaws having corresponding ratchet teeth, a threaded element movable relatively to said driving jaw and into abutting engagement therewith to hold said ratchet teeth engaged, and means including said threaded element for causing an initial, limited degree of rotation of both said clutch elements prior to movement of said engine member.

4. The combination with an engine member of means for driving said member comprising a one-way driving connection including coaxially disposed driving and driven clutch jaws having corresponding ratchet teeth, means including a threaded element movable relatively to said driving jaw and into abutting engagement therewith to hold said ratchet teeth engaged, and means for causing an initial, limited degree of rotation of both said clutch elements prior to movement of said engine member, said means including said threaded element, a driving member in line with

said threaded element, and a second clutch of the friction type acting to drivably connect said driving member and threaded element.

5. The combination with an engine member of means for driving said member comprising a one-way driving connection including coaxially disposed driving and driven clutch jaws having corresponding ratchet teeth, means including a threaded element movable relatively to said driv-

ing jaw and into abutting engagement therewith to hold said ratchet teeth engaged, and means including a gear having a threaded extension engaging said threaded element for causing an initial, limited degree of rotation of both said clutch elements prior to movement of said engine member. 5

RAYMOND P. LANSING.
